NELSON FULCHER, OF SAULT STE. MARIE, ONTARIO, CANADA.

TRACK-LINING ARCH.

1,114,460.

Specification of Letters Patent.

Patented Oct. 20, 1914.

Application filed June 25, 1914. Serial No. 847,800.

To all whom it may concern:

Be it known that I, NELSON FULCHER, a subject of the King of Great Britain, and resident of Sault Ste. Marie, Province of Ontario, Dominion of Canada, have invented certain new and useful Improvements in Track-Lining Arches, of which the following is a specification.

This invention relates to alinement adjusting mechanisms adapted to be used on railway tracks and the objects of the invention are to facilitate in the adjusting of the alinement of such tracks, to render the device easily transferred from one section of the track to another, to permit of both rails of the track being simultaneously adjusted in either lateral direction, to simplify and reduce the number of working parts of the mechanism, and generally to adapt the several parts to better perform the functions required of them and it consists essentially of the improved construction of mechanism particularly described and set forth in the following specification and accompanying drawings forming a part of the same.

In the drawings: Figure 1 is a perspective view of the improved adjusting mechanism. Fig. 2 is a sectional elevation of the arch showing the manner of fixing the same to the railway track.

Like characters of reference refer to like parts in the several drawings.

Referring to the drawings A represents a railway track with the improved adjusting mechanism B mounted thereon, such railway tracks being of usual construction and well known in the art require no further description.

The mechanism B comprises the arch 1 which is substantially of inverted U-shape in cross section, such arch having orifices 2, 3 and 4 extending through its upper side and being provided with transversely extending brackets 5, and 6 mounted on the ends thereof and preferably formed integral therewith, such brackets terminating in bifurcated ends 7 and 8 having orifices therethrough. Transverse members 9 and 10 extend between the lateral parallel sides of the arch 1 and are formed integral therewith, such members being adapted to form with the under face of the transversely extending brackets 5 and 6 suitable slots 9^a and 10^a the object of which will be made clear hereafter. The arch 1 is provided with orifices 11 extending through the parallel sides thereof

with which the pin 12 is designed to engage, such pin having the socket 13 pivotally mounted thereon. This arch is designed to be superposed on the track A and is provided with wheels 14 and 15 rotatably mounted on the bolts 16 and 17 in the bifurcated ends 7 and 8, such wheels being adapted to engage with the rails of the said track.

To facilitate in securing the arch 1 in a desired fixed position on the track, wedge members 18 are provided which slidably engage with the slots 9^a and 10^a, such wedge members being pivotally mounted on the lower end of one of the arms of the cranks 19 which are rotatably mounted in the parallel sides of the said arch, such cranks being rigidly connected to the lower end of the links 20, the upper ends of such links being pivotally attached to one end of the connecting rods 21, the other end of said connecting rods being pivotally connected to the lever 22, which is in turn pivotally mounted intermediate of its ends on the arch 1, the said connecting rods engaging with the said lever on opposite sides of the fulcrum thereof. It is frequently found expedient to adjust the gripping of the wedge members 18 and to this end the connecting rods 21 are made in two portions having the adjacent ends 80 provided with right and left handed threads respectively with which the couplings 23 are designed to engage.

A U-shaped bracket 24 is suitably fixed to the arch 1 and designed to embrace the lever 22, such bracket being provided with an upwardly extending arm 25 to which the dog 26 is pivotally mounted.

27 represents a jack which is of any suitable type, the screw or ram of which is adapted to engage with its upper end the socket 13, such jack being well known in the art need not further be enlarged upon.

The operation of the device is as follows: The arch 1 is placed over the track with the wheels 14 and 15 engaging the rails, the said arch being then pushed along the track to a point at which the alinement is to be adjusted, when the lever 22 is operated causing the wedge members 18 to simultaneously engage with the under side of the rail head, the said lever being then locked in position by the dog 26 which is rotated to engage with the edge thereof. The jack 27 is now placed in position with the base engaging the track bed and the upper end of the jack screw engaging with the socket 13 whereupon when

the jack is operated the track is pressed in the desired direction when the railway ties are then securely ballasted to the track bed.

When the alinement of one section of the track has been completed the dog 26 is disengaged from the lever 22 which is then operated to simultaneously release the wedge members 18 thereby rendering the arch capable of being moved to another section of the track.

To obviate the disengaging of the jack 27 each time an operation has been performed and the arch is to be moved to another section of the track, a chain or caption member 28 is provided which is secured at one end to the arch, the other end of the said chain being utilized to hitch up the jack clear of the track so permitting of the arch when the wedge members 18 are released being freely transferred from section to section.

As many changes could be made in the above construction and many apparently widely different embodiments of my invention, within the scope of the claims, constructed without departing from the spirit or scope thereof, it is intended that all matter contained in the accompanying specification and drawings shall be interpreted as illustrative and not in a limiting sense.

30. What I claim as my invention is:

1. A device of the class described comprising an arch designed to be located over a railway track, brackets mounted on the ends of the said arch, such brackets being provided with bifurcated ends, wheels pivotally mounted in the said bifurcated ends, such wheels being designed to engage with the rails of the said track, means for securing the arch to the said railway track, and 40 means for adjusting the alinement of the said track, as and for the purpose specified.

2. A device of the class described comprising an arch substantially U-shaped in cross section, such arch being designed to be located over a railway track, transversely extending brackets mounted on the ends of the said arch, such brackets being provided with bifurcated ends, wedge members adapted to engage with the rails of the said track, 45 means for operating the said wedge members and means for adjusting the alinement of the said track, as and for the purpose specified.

3. A device of the class described comprising an arch designed to be located over a railway track, brackets mounted on the ends of the said arch, such brackets being provided with bifurcated ends, wheels rotatably mounted in the said bifurcated ends, 55 wedge members adapted to engage with the rails of the said track, means of operating the said wedge members comprising cranks, links, connecting rods, and a lever, means for adjusting the length of the said connecting rods and means for adjusting the aline- 65

ment of the said railway track, as and for the purpose specified.

4. A device of the class described comprising an arch adapted to be located over a railway track, brackets mounted on the end of the said arch, such brackets being provided with bifurcated ends, wheels rotatably mounted in the said bifurcated ends, wedge members adapted to engage with the rails of the said track, means for simultaneously operating the said wedge members and a jack designed to engage with the said arch, as and for the purpose specified.

5. A device of the class described comprising an arch designed to be located over a railway track, wedge members adapted to engage with the rails of the said track, means for simultaneously operating the said wedge members, means for retaining the said wedge members in a locking position and means for adjusting the alinement of the said track, as and for the purpose specified.

6. A device of the class described comprising an arch designed to be located over a railway track, wedge members adapted to engage with the rails of the said track, a lever pivoted intermediate of its ends to the said arch, such lever being adapted to simultaneously operate the said wedge members, a U-shaped bracket mounted on the said arch adapted to embrace the said lever, a dog pivotally mounted on the U-shaped bracket and adapted to engage with the said lever and means for adjusting the alinement of the said railway track, as and for the purpose specified.

7. A device of the class described comprising an arch adapted to be located over a railway track, wedge members designed to engage with the rails of the said track, a lever pivotally mounted intermediate of its ends to the said arch, connecting rods pivotally mounted to the said lever on opposite sides of the fulcrum thereof, such rods being designed to operate the said wedge members, the said connecting rods being made in two portions terminating in threaded ends, a coupling designed to engage with the said threaded ends, and means for adjusting the alinement of the said track, as and for the purpose specified.

8. A device of the class described comprising an arch substantially U-shaped in cross section designed to be located over a railway track, such arch being provided with orifices extending through the parallel arms thereof, means for securing the said arch to the said track, a pin designed to engage in the said orifices, a socket pivotally mounted on the said pin and a jack adapted to engage on the upper end in the said socket, as and for the purpose specified.

9. A device of the class described comprising an arch substantially U-shaped in cross

section designed to be located over a railway track, such arch being provided with orifices extending through the parallel arms thereof, means for securing the said arch to the said track, a pin designed to engage in the said orifices, a socket pivotally mounted on the said pin, a jack adapted to engage on the upper end in the said socket, and a chain adapted to be connected at one end to the

said arch and at the other end to the said jack, as and for the purpose specified.

In witness whereof I have hereunto set my hand in the presence of two witnesses.

NELSON FULCHER.
